UNITED STATES PATENT OFFICE.

CLYDE WALTER HATFIELD, OF EMERSON, IOWA.

GRAIN-CAR DOOR.

Application filed May 25, 1923. Serial No. 642,342.

To all whom it may concern:

Be it known that I, CLYDE WALTER HATFIELD, a citizen of the United States, residing at Emerson, in the county of Mills and State of Iowa, have invented certain new and useful Improvements in Grain-Car Doors, of which the following is a specification.

This invention relates to certain new and useful improvements in grain-car doors, and it has for its objects among others to provide a simple, cheap, yet efficient and serviceable sectional grain-car door that can be readily applied by unskilled labor and which shall serve most effectually to prevent the escape of grain or other commodities which it is desired to transport in the car.

As a rule, railroad companies contract for grain-car doors from the manufacturers, and the same are shipped by carload lots to division points and unloaded and piled up in large piles for distribution to smaller stations along the line when the agents order from five hundred to two thousand, more or less, to a place where they have to be again handled after being reloaded and shipped. This takes up extra cars which could be used for other purposes, in addition to the number of men required to reload them and then unload them, the latter taking the section force at the station, all of which makes it an expensive transaction. Furthermore, in most places these doors are left where they are unprotected, and many are stolen and used by farmers and others. In addition to this, the grain-car doors are usually nailed to the car doors by non-experienced men, with the result that the doors do not properly fit, resulting in leakage of grain and other material, which results in a loss claim against the railroad company which amounts to a very considerable sum during the course of a year. Then again, when the cars reach their destination the doors are torn off by crowbars and the like which splits up the door or makes holes therein so that the door is either unfit for further use, or if put to use another door has to be employed to cover up the holes. Another item which amounts to many dollars during the year is the paper which is employed, being nailed around the doors in an attempt to keep the grain from leaking out. This is not necessary by the use of my improved door.

My improved door can be readily placed in position. It can be opened section by section or all together as may be desired. It is always ready for service, can be closed in a short time, no nailing required, and by the employment thereof in most instances the car can be gotten ready for the train which is to take it to its destination in a short time so that the train will not have to wait and the car will not be left, thus saving one day's delay in getting the contents to the market or to its destination.

Other objects and advantages of the invention will hereinafter appear and the novel features thereof will be particularly pointed out in the appended claims.

The invention is capable of embodiment in a variety of forms, an efficient one of which is herein shown without, however, limiting myself to the same.

The invention in such form is clearly illustrated in the accompanying drawings, which, with the numerals of reference marked thereon, form a part of this specification, and in which

Figure 1 is the front elevation showing a portion of a car equipped with one of my improved sectional doors.

Figure 2 is an enlarged cross section on the line 2—2 of Figure 1, looking in the direction of the arrows.

Figure 3 is an enlarged perspective detail of one form of locking means.

Figure 4 is an enlarged detail of a portion of one of the doors with a part in section.

Figure 5 is an edge view of Figure 4, with a portion broken away.

Figure 6 is an enlarged section on the line 6—6 of Figure 4, looking in the direction of the arrows.

Figure 7 is a section on the line 7—7 of Figure 1.

Figure 8 is a front elevation of one of the sections of the door on an enlarged scale, with portions broken away and parts in section.

Figure 9 is an enlarged perspective detail showing a portion of the rod and means for supporting the upper section of the door.

Like numerals of reference indicate like parts throughout the several views.

Referring to the drawings—
1 designates a portion of the wall of a car, and 2 the door opening therein.

Within the car at one side of the said door

opening is a post or block 3, while above the door opening therein is secured a rod or rail or the like 4, supported in any suitable manner and forming a means on which the upper 5 door is guided in its movements, in the present instance by means of staples or loops or the like 5 secured to the top edge 6 of the upper section of the door as seen in detail in Figure 9.

10 The different door sections are substantially alike in all particulars except as hereinafter specified, being formed preferably of sheet metal and comprising a central panel portion 7^a and hollow stiles 8, see Figure 7. 15 As shown in the present instance the panel material is extended at top and bottom and suitably shaped to form the horizontal portion 9, the vertical member 10 and the horizontal portion 11, the vertical portion 12 the vertical member 14 connected with the vertical member 12 by the short horizontal member 13, and the member 14 terminating in the inwardly-extended horizontal member 15, all as clearly seen in Figure 7. The other 20 portion of the stile is formed by a piece of metal which is formed into the horizontal member 16 at one end, from which extends the vertical member 17 with the lateral member 18, the short vertical member 19, the short horizontal member 20, the vertical member 21 and the inwardly-extending horizontal member 22, all as also clearly shown in Figure 7. All of these 25 parts may be stamped or otherwise formed, and at the junction of the panel portion 7^a and the members 9 and 16 I have shown angle irons 23 and 24 which are secured in any suitable manner as seen at 25 to the members 7^a, 9 and 16 so as to reinforce the 30 same at these points and form a light yet strong door section.

The door may be composed of as many sections as may be desired, in the present instance shown as composed of four, although 45 this number may be varied. The various sections are arranged upon the inside of the car, as seen in Figure 2, and in Figure 1 which is a front elevation looking from the inside of the car. The various sections can be operated, one at a time or all may be actuated in 50 unison when necessary. As above stated, the upper section is supported at the upper edge on the track as seen in Figure 1, and within the lower rail thereof there is mounted on a 55 suitable axle or the like 26 a roller 27, of which there may be as many as one may deem necessary, which roller or rollers travel on a track 28 formed on the next adjacent section and arranged within the lower hollow 60 panel of the section as seen in Figure 6. This roller-supporting track may be of any desired and convenient form, but in the present instance I have chosen to show it as formed of the stile of the next adjacent section, 65 see Figure 6, the panel 7^a being extended to

engage the inner wall of the top horizontal member of the stile to give the requisite strength and support for the roller, the depending portion being designed to work through a slot between the horizontal members 15 and 22 as seen clearly in Figure 6. The panel and the depending members of the panel in this view are secured together outside the slot by suitable means 30, which 70 also serve to secure thereon the angular reinforcing member 31 the horizontal member of which serves to limit the downward movement or sag of the next upper section. It is to be noted that there is sufficient space 75 32 between the horizontal members 15 and 22 and the horizontal members 11 and 18 to permit of any reasonable amount of sag of the section within possible bounds without its binding.

Within the hollow depending portion of the lower section of the door there is mounted on a suitable shaft or axle 33 a roller 34 that travels on a track 35 which is arranged within a trough or channel 36 below the level of the floor of the car, or below the lower edge of the lower section of the door. In the present instance this trough or channel is formed by the member 37, from which the track 35 is formed as seen in Figure 7.

Within the hollow depending portion of the lower section of the door there is mounted on a suitable shaft or axle 33 a roller 34 that travels on a track 35 which is arranged within a trough or channel 36 below the level of the floor of the car, or below the lower edge of the lower section of the door. In the present instance this trough or channel is formed by the member 37, from which the track 35 is formed as seen in Figure 7. The sections of the door are arranged so that they overlap to form tight joints and further so that when the one section is moved to closed position the next adjacent section will be moved with it, providing it is open. One way of accomplishing this is by crimping the upper edge of the wall 38 as seen at 39 in Figure 8. The walls at opposite edges of the sections are as seen in Figure 8 of different heights, the one wall 40 at one edge being of less height than the wall at the other edge so as to leave at the latter point a depending portion 41, as seen in Figure 8.

The panels of the sections are reinforced and braced by the angle irons 42 as seen in Figures 2, 4 and 8, at their opposite vertical edges.

Each section is shown as provided with a handle 43 near the front end of the section and at about the mid height of the section as seen in Figures 1, 2 and 4. These handles serve as convenient means for opening the sections. They are disposed on the inside face of the sections except the top one where the handle is placed on the outer face of the door, as indicated by dotted lines in Figure 1.

Each section may be locked in its closed position in any suitable manner; in the present instance I have shown each as provided with a staple or the like 44 for co-operation with a pivoted hasp or the like 45 on a fixed member 46. Each section may, if desired, be provided with two of such fastening devices, one near the top and one near the bottom, as seen in Figure 1, with 125 130

the exception of the top section, and this is provided upon the outside with a staple or the like 47 for cooperation with the hasp or the like 48 pivoted to the post or block 3 as seen in Figure 2 and disposed angularly as seen clearly in said Figure 2.

Furthermore, each section except the top is provided with a spring locking device; this is arranged preferably near the top edge of each section except the top. It comprises a metallic bar 49 secured to the under face of the upper portion of the underlying face 50 of the section, by screws or the like, as seen best in Figure 3 and at one end 10 has the depending portion 51 terminating in the free lateral member 52 which extends substantially parallel with the said underlying face 50, as clearly shown in said Figure 3. On the panel of the next lower section is a lock case 53 in which is mounted a spring bolt 54 the face of which is beveled as seen at 55 in Figure 3, while extended from the upper face of the said lock case is a lug 56 which terminates in the lateral member 57 which overlies the projecting end of 25 the bolt 54 as shown. When the one section is closed with respect to the next, the member 52 will strike the beveled end of the bolt and force the same inward against the action of the spring thereof till the member 52 has passed the bolt when the latter will be thrown outward by the spring and will engage in front of the member 52 and thus hold the section locked in closed position. 30

35 The bolt is provided with a finger piece 58 slidable in the slot 59 in the wall of the case as seen in Figure 3, and by which the bolt may be easily withdrawn when it is desired to open the section.

40 On the edge of the door opposite to the edge carrying the staples 44 is a member 60 similar to the member 49 just described, and which is designed to engage a similar lock 61 secured to the wall of the car in such 45 position, that when the section is thrown open and the door not in use the bottom section will be automatically locked and thus all the sections will be held in such open position; the said lock is placed near the 50 top of the bottom section as seen in Figure 1.

55 62 are uprights within the car which serve as guides for the sections of the door in their sliding movements and also to keep them in proper position and prevent rattling or undue lateral movement.

60 The member 46 hereinbefore mentioned has a flange 63 which is secured to the post or block 3 by suitable means 64, the said member being made hollow as seen in Figure 2, being bent or shaped to form the main body portion 65 which lies against and is secured to the post or block 3 by the same means that secures the flange 63, and the front wall to which the securing hasp 45 is pivoted, while the wall adjacent or cooper-

ating with the adjacent stile of the door section, is formed as seen clearly in Figure 2, with the indented or oppositely inclined wall forming a trough or the like into which is adapted to snugly fit the oppositely formed 70 portion 66 on the side stile of the door section. The opposite edge of the door is provided with the offset member 67 secured to its stile as seen in Figure 2, and having the trough-shaped portion or member 68 which is adapted to fit into the correspondingly shaped trough 69 of the member 70 which is disposed between the stile 71 and the wall 1 of the car. This gives offset grain tight 75 interengaging members which will most effectually prevent leakage of the grain or other commodity carried in the car. 80

85 By "trough-shaped member" I mean a member in which the walls instead of being right-angled to each other are upon inclined lines, so that when the two opposed trough-shaped members are brought together, as seen in Figure 2, there is a wedging fit that precludes escape of the grain.

90 It is to be noted that the member 70 is the same thickness as the post or block 3 so that the door will move in a straight plane as it is slid back and forth, as seen in Figure 2. When the sections are closed these interfitting portions will preclude escape of the 95 material from the car.

100 It is further to be noted that the door is entirely within the confines of the car and hence cannot be injured or damaged in any way during transportation, and no crow bars or the like are required to open the same when the car reaches its destination.

105 Modifications in details of construction, proportion of parts etc. may be resorted to without departing from the spirit of the invention or sacrificing any of its advantages.

110 What is claimed as new is:—

115 1. A horizontally-slidable sectional grain car door, wedgingly interfitting trough-shaped members interposed between the stile of the door and a wall of a car, and a fixed upright between which and the said wall of the car said stile and its trough-shaped member is guided.

120 2. A grain-car door having its side portions provided with trough-shaped portions, that at one side being offset from that on the other side, and correspondingly offset cooperating portions affixed to the car for wedging cooperation therewith.

125 3. A grain car door in sections movable independently of each other, overlapping means on said sections, and means whereby when one section is moved to closed position the next section will be moved with it, the walls at opposite edges of the sections being of different heights.

130 4. A grain car door in sections movable independently of each other, overlapping

means on said sections, means whereby when one section is moved to closed position the next section will be moved with it, the walls at opposite edges of the sections being of different heights, and cooperating locking devices on the adjacent sections automatically engaged by the closing movement of one section with relation to the next adjacent one.

5. A grain-car door formed of horizontally-slidable overlapping sections movable independently of each other, means offset at one edge of the sections for forming a tight joint between them, said means being of oppositely extended trough-shapes, means for locking each in closed position, and means for locking them all in open position.

6. A grain-car door formed of horizontally-slidable overlapping sections movable independently of each other, means offset at one edge of the sections for forming a tight joint between them, said means being of oppositely extended trough-shape, means for locking each in closed position, means for locking them all in open position, and roller supports for one of the sections.

7. A grain-car door section having a hollow rail, a roller carried by the rail within

the hollow thereof, a track upon which said roller travels, and cooperating means on the track and carried by the rail for limiting the vertical movement of the section.

8. A grain car door formed in horizontally-slidable independent sections having wedging-shaped means at the edges for engagement with cooperating interfitting means at opposite edges of the door frame to form wedging tight joints, that at one edge being offset from the plane of the door to bring the interfitting means in different planes at opposite edges of the door, and means for automatically locking the bottom section to hold all of the sections in open position.

9. A grain-car door section comprising a panel and a stile formed in part of an extension of said panel, opposite edges of the panel having hollow members one wall of each of which is trough-shaped for cooperation with a relatively fixed trough-shaped part to form a tight joint and a cooperating part secured to the panel and reinforced at its connection therewith.

In testimony whereof I affix my signature.

CLYDE WALTER HATFIELD.
